DESIGN FOR A MATCH BOOK DISPENSER

Harry W. Burge, Overland, Mo.

Application May 13, 1946, Serial No. 129,638

Term of patent 14 years

(Cl. D48—28)

To all whom it may concern:

Be it known that I, Harry W. Burge, a citizen of the United States, residing at Overland, county of St. Louis, State of Missouri, have invented a new, original, and ornamental Design for a Match Book Dispenser, of which the following is a specification, reference being made to the accompanying drawing, forming a part thereof, in which Figure 1 is a front perspective view of a match book dispenser embodying my new design; Figure 2 is a rear perspective view thereof; Figure 3 is a bottom plan view thereof; and Figure 4 is a fragmentary vertical sectional view taken along line 4—4 of Figure 3.

I claim:

The ornamental design for a match book dispenser, substantially as shown.

HARRY W. BURGE.
